UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,829.

Specification for Design.

Patented Jan. 5, 1915.

Application filed September 11, 1914. Serial No. 861,315. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design for a corner piece for coffins comprises angularly arranged lengthwise faces having a lengthwise embossed figure 1 at their juncture, and an embossed U-shaped figure 2 with its central portion beneath the lower end of the figure 1 and its arms at opposite sides thereof, said figure 2 having lengthwise and crosswise ridges 3,

4, and giving the general appearance of a pall hanging in a plurality of folds on opposite sides of the figure 1 and along side edges of the corner piece. The side edges of the figure 1 flare outwardly at the top of the corner piece and the upper end of said figure 1 is formed with a central spherical protuberance 5.

I claim:—

The ornamental design for a corner piece for coffins, and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
